UNITED STATES PATENT OFFICE.

LEWIS T. HOUGHTON, OF WORCESTER, MASSACHUSETTS.

YARN-TENSION MACHINE.

1,382,730.

Specification of Letters Patent. Patented June 28, 1921.

Application filed May 22, 1919. Serial No. 298,908.

To all whom it may concern:

Be it known that I, LEWIS T. HOUGHTON, a citizen of the United States, residing at Worcester, in the county of Worcester and 5 State of Massachusetts, have invented a new and useful Yarn-Tension Machine, of which the following is a specification.

This invention relates to an improvement in a yarn tension device of the general type 10 shown in my prior Patent No. 1,303,202, in which type of tension device the yarn is guided between two series of tension members or guides, preferably alternately arranged.

15 It is very important in this type of tension device that the yarn tension be maintained substantially constant throughout the entire winding of a spool and whether the spool is full or substantially empty. The 20 winding speed varies greatly as the empty spool fills up and is often more than twice as great with a full spool, making it a matter of great difficulty to maintain uniform tension with such wide variations in 25 winding speed. In fact, it is not uncommon to provide speed changing devices in winding machines, as heretofore used, to overcome this difficulty. Furthermore it is important that the device shall be adapted to 30 yield whenever sudden tension is placed on the yarn, which often occurs when the yarn on the bobbin becomes embedded between other adjacent layers of yarn.

It is the general object of my present invention to provide improved means for so 35 applying tension to the yarn that substantially uniform tension may be maintained in every operative position of the tension members and under all conditions of operation, 40 said means being preferably adjustable to vary the tension.

My improved tension means is also adapted to hold the tension members yieldingly in 45 inoperative position when manually moved to such position.

Other features of my invention relate to an improved supporting stand, and to an improved form of bobbin support.

50 My invention further consists in certain arrangements and combinations of parts which will be hereinafter described, and more particularly pointed out in the appended claims.

A preferred form of my invention is shown in the drawings, in which— 55

Figure 1 is a side elevation of my improved tension device;

Fig. 2 is a front elevation thereof;

Fig. 3 is a plan view thereof;

Fig. 4 is a side elevation looking in the 60 direction of the arrow 4 in Fig. 2, and

Fig. 5 is a sectional view, showing a slight modification.

Referring to the drawings, I have indicated a bobbin B from which the yarn Y is 65 wound by the spool S. My improved tension device is mounted on a longitudinally extending bar 10 forming part of a spooling or rewinding machine.

The tension device proper comprises a 70 stand 11 in which a plurality of guide rods 12 are fixed, being preferably bent downward and extending in parallel relation toward the right, as viewed in Fig. 3. The stand 11 is preferably formed of sheet metal with a U-shaped extension 13 on the rear side embracing the supporting rod 10, and clamped around said rod or bar by a bolt 14.

A bracket 15 also preferably formed of 75 sheet metal is secured to the front face of the stand 11 by a bolt 16 and nut 17 extending through a slot 18 in the bracket. Forwardly projecting flanges on the stand restrict the bracket to vertical movement only.

A plurality of tension fingers 19 are 80 mounted in a support 20 fixed to a rod or shaft 21 extending through ears 22 on the bracket 15 and having a handle portion 23 at the forward end thereof. The lower limit of movement of the tension fingers is determined by the engagement of a portion of the support 20 with some portion of the bracket 15, such as that which supports the ears 22.

The support 20 is provided with a cam 95 portion which may be a separate cam plate 24 secured to the support, as shown in Figs. 1 to 4, or which may be made by forming the support itself in the shape of a cam as shown at 25 in Fig. 5. A flat spring 26 is secured at 27 to an ear 28 formed on the bracket 15 and extends upwardly to engage the cam 24 at a point below the level of the axis of the shaft 21.

An adjusting screw 29 threaded in a nut 105 30 extends freely through a hole in an ear

31 on the bracket 15, and is provided with a check-nut 32 outside of the ear 31. The nut 30 is so engaged by the bracket 15 that it cannot rotate, and when the screw 29 engages the spring the nut 30 is also held firmly against the ear 31.

The check nut 32 and also the nut 17 by which the bracket 15 is secured in adjusted position are preferably of irregular outline 10 and require a special wrench for adjustment. This prevents unnecessary and inaccurate adjustments by unauthorized persons when installed in a mill.

As the spring 26 engages the cam 24 at a 15 point below the axis of the shaft 21 the spring has a constant tendency to swing the tension fingers 19 downward, and the cam 24 is so designed that the tension of the spring is substantially constant in all operative positions of the tension fingers.

When however, the fingers are moved to inoperative position, as shown in dotted lines in Figs. 3 and 5, the end of the spring 26 engages the under side of the cam 24 and 25 yieldingly holds the fingers in raised position. The operation of the cam shaped support 25, as shown in Fig. 5, is exactly the same as that of the cam 24 shown in Figs. 1 and 4.

30 I have also shown in the drawings an improved construction of bobbin support comprising a rigid member 35 extending vertically downward and secured to the stand 11 by the bolt 14 which clamps the stand to 35 the supporting bar 10. The member 35 is preferably formed of sheet metal and of substantially U-shaped cross section and the side flanges thereof closely embrace the depending U-shaped portion 13 of the stand 40 11, thus preventing lateral movement of the member 35 relative thereto.

One of the flanges 36 of the part 35 increases in width at its lower end and is provided with a vertical slot 37. A horizontally slotted arm 38 is clamped to the flange 36 by a bolt 39, said arm being provided with a horizontal portion 40 upon which a dead spindle 41 is mounted. The spindle 41 is provided with a head 42 firmly seated 50 upon the portion 40 by a spring 43 contained in a cap 44 having downwardly extended lugs by which it is clamped to the portion 40, as shown in Fig. 3.

The cap 44 is slotted at 45 to permit the 55 spindle 41 to be swung forward or to the left as viewed in Fig. 1 for easy insertion or removal of the bobbin B. No claims are made to the structure of the dead spindle in this application, as claims covering said structure have been heretofore presented in my prior application Serial No. 108,063, filed July 7, 1918.

Having thus described my invention, it 60 will be seen that I have provided a yarn tension device of simple and durable con-

struction and that I have provided an extremely efficient means for applying tension to the fingers 19 and for adjusting the tension to suit varying conditions. I have found in practice that this tension device 70 is capable of controlling the tension when yarn is drawn through the same at speeds much higher than has been heretofore considered practicable in a spooling machine, and I have found that the tension is substantially unchanged whether either the bobbin or the spool is substantially full or substantially empty, and also whether the bobbin is warp wound or filling wound.

Having thus described my invention, it 80 will be evident that changes and modifications can be made therein by those skilled in the art within the scope of my invention as set forth in the claims, and I do not wish 85 to be otherwise limited to the details herein described but what I claim is:—

1. A yarn tension device comprising two series of yarn guides adjustable toward and from each other to secure a desired normal tension and a means independent of said adjustment whereby increase of tension on the 90 yarn automatically and substantially reduces the normal tension space between the guides, while maintaining the tension substantially unchanged, substantially as described.

2. A yarn tension device comprising two series of tension members adjustable toward and away from each other and means independent of said adjustment to maintain normal tension on the yarn while permitting 100 substantial changes in the relative separation of said members.

3. A yarn tension device for spooling 105 yarn, having in combination, two series of tension guides, one of said series being pivotally mounted and adjustable toward and from the other series, and means independent of said adjustment for yieldingly holding the pivoted series in a position to furnish 110 the desired yarn tension but permitting said series of guides to automatically and substantially change the tension space between the two series to relieve increased pull on the 115 yarn while maintaining substantially uniform yarn tension.

4. A yarn tension device, comprising a plurality of fixed guide rods, a plurality of tension fingers mounted upon a pivoted support and alternating therewith, and means to apply yielding tension to said fingers, said means comprising a spring having continuous sliding engagement with a portion of 120 said support below the axis thereof and effective to yieldingly and substantially uniformly resist displacement of said fingers from their lowermost position.

5. A yarn tension device, comprising a plurality of fixed guide rods, a plurality of tension fingers mounted upon a pivoted sup- 130

- port and alternating therewith, and means to apply yielding tension to said fingers, said means comprising a cam-shaped portion of said support, and a spring engaging said portion to yieldingly depress said fingers. 5
6. A yarn tension device, comprising a plurality of fixed guide rods, a plurality of tension fingers mounted upon a pivoted support and alternating therewith, and means 10 to apply yielding tension to said fingers, said means comprising a cam-shaped portion of said support, a flat spring engaging said portion, and means to adjust the tension of said spring.
- 15 7. A yarn tension device, comprising a plurality of fixed guide rods, a plurality of tension fingers mounted upon a pivoted support and alternating therewith, and means to apply yielding tension to said fingers, said 20 means comprising a spring continuously engaging a portion of said support below the axis thereof and normally acting to yieldingly resist displacement of said fingers from their lowermost position, the action of 25 said spring being reversed when the fingers are turned upward to inoperative position.
8. A yarn tension device, comprising a plurality of fixed guide rods, a plurality of tension fingers mounted upon a pivoted support and alternating therewith, and means 30 to apply yielding tension to said fingers, said means comprising a cam-portion on said support extending downward below the axis of said support when the latter is in operative 35 position, and a spring engaging said cam portion below said axis.
9. A yarn tension device, comprising a plurality of fixed guide rods, a plurality of tension fingers mounted upon a pivoted sup-
- port and alternating therewith, and means 40 to apply yielding tension to said fingers, said means comprising a cam-shaped portion on said support, a flat spring fixed at one end and engaging said portion at the other end, and an adjusting screw engaging said 45 spring at an intermediate portion thereof.
10. In a yarn tension device for a machine having a longitudinally extended supporting bar, in combination, a plurality of fixed and movable tension members, a stand on 50 which said members are mounted, said stand having a U-shaped attaching portion and means to clamp said portion of said stand about the supporting bar.
11. A yarn tension device, comprising a 55 stand, a plurality of fixed and movable tension members mounted thereon, a depending bobbin support, said stand having a depending portion fitting between the sides of said support to preserve the lateral alinement 60 thereof, and a single fastening device adapted to secure said bobbin support to said stand and to clamp said stand to a supporting bar.
12. A yarn tension device comprising two 65 series of tension members, means permitting adjustment of said members to provide a normal space between said series, one of said series being movable independent of said adjustment a substantial distance toward the 70 other series to relieve increased yarn pull, and means to maintain substantially uniform tension on said movable series in every operative position thereof.

In testimony whereof I have hereunto af- 75 fixed my signature.

LEWIS T. HOUGHTON.
